DESIGN FOR A GLOVE

Isabel Ireland, New York, N. Y.

Application March 30, 1936, Serial No. 61,841

Term of patent 3½ years

To all whom it may concern:

Be it known that I, Isabel Ireland, a citizen of the United States of America, residing in Manhattan, county of New York, and State of New York, have invented a new, original, and ornamental Design for a Glove, of which the following is a specification, reference being had to the accompanying drawing, forming part thereof, wherein,

The dominant feature of my design resides in the tubular lacings on the rear surface of the glove.

I claim:

The ornamental design for a glove, substantially as shown, and described.

ISABEL IRELAND.
